CLAIM

The ornamental design for a protective cover for automotive front end, as shown and described.

DESCRIPTION

FIG. 1 is a left front perspective view of a protective cover for automotive front end that is installed onto an automobile; FIG. 2 is a front elevational view of the protective cover for an automotive front end of FIG. 1 as installed onto an automobile;

FIG. 3 is a left front perspective view of a first variant of a protective cover for automotive front end;

FIG. 4 is a front elevational view of the protective cover for automotive front end of FIG. 3;

FIG. 5 is a rear elevational view of the protective cover for automotive front end of FIG. 3;

FIG. 6 is a top plan view of the protective cover for automotive front end of FIG. 3;

FIG. 7 is a bottom plan view of the protective cover for automotive front end of FIG. 3;

FIG. 8 is a left side elevational view of the protective cover for automotive front end of FIG. 3;

FIG. 9 is a right side elevational view of the protective cover for automotive front end of FIG. 3;

FIG. 10 is a magnified view of a portion of the protective cover for automotive front end of FIG. 1;

FIG. 11 is a left front perspective view of a second variant of a protective cover for automotive front end;

FIG. 12 is a front elevational view of the protective cover for automotive front end of FIG. 11;

FIG. 13 is a top plan view of the protective cover for automotive front end of FIG. 11;

FIG. 14 is a bottom plan view of the protective cover for automotive front end of FIG. 11;

FIG. 15 is a left side elevational view of the protective cover for automotive front end of FIG. 11;

FIG. 16 is a right side elevational view of the protective cover for automotive front end of FIG. 11; and,

FIG. 17 is a rear elevational view of the protective cover for automotive front end of FIG. 11.

The broken lines shown in the drawings are for illustrative purposes only and form no part of the claimed design.
